United States Patent Office.

JOHN T. COE, OF CHAMBERSBURG, PENNSYLVANIA, ASSIGNOR TO HIMSELF
AND EDWARD F. COE, OF SAME PLACE.

Letters Patent No. 74,505, dated February 18, 1868.

IMPROVEMENT IN CHURNS.

The Schedule referred to in these Letters Patent and making part of the same.

TO ALL WHOM IT MAY CONCERN:

Be it known that I, JOHN T. COE, of Chambersburg, in the county of Franklin, and State of Pennsylvania, have invented a new and improved Churn; and I do hereby declare that the following is a full, clear, and exact description of the construction and operation of the same, reference being had to the accompanying drawings, and letters of reference marked thereon, making a part of this specification, of which—

Figure 1 is a plan view.

Figure 2, a side elevation of the bevel-gearings.

Figures 3 and 4, sectional views of the dasher.

Figure 5, a view of the band *c*.

This invention consists in the construction and arrangement of a pair of dashers in such manner as to draw together the particles of butter formed in the operation of churning, into one mass in the centre of the churn, as will hereinafter more fully appear.

To enable others skilled in the art to make and use my invention, I will proceed to describe its construction and operation.

A represents a churn of ordinary construction, made oblong in this instance, which, however, is not necessarily the form to be adopted. At two points in the longitudinal central line are bearings at equal distance from the ends of the churn, in which are stepped the journals of the two vertical dashers *b*, which are supported at their tops by bands *c*, at the centre of which are circular holes for the reception of the journals *a'* *a''* on the upper ends of the said dashers. The bands *c* are each pivoted at one end, as seen at *d*, fig. 5, and at their other ends are bent into the form of hooks *d'* *d''*, which hooks are inserted in staples *e* in such manner as to be removed therefrom without any difficulty on taking off the cover, and thus admit of the easy adjustment of the dashers *b*. In the tops of the journals *a'* *a''* are hollows made to fit the ends of the shafts *h* *h* of the bevel-gears *i*, said shafts being set in casings *h'* *h''*, rigidly placed in the cover of the churn. The lower ends of the casings *h'* *h''* project downward far enough to meet the upper ends of the hollow journals *a'*, and thus prevent the dasher from jumping during the operation of the machine, so as to displace the bands *c* from their staples. The shafts *h* are adjustable in their casings *h'*, and mesh with bevel-gears *k* *k* on the shaft *k'*, said shaft being supported in standards *l* *l* at the ends of the cover. The bevel-gears *k* are set back to back, so as to impart motion in contrary directions to the gears *i*, and through them to the dashers *b*. The dashers are each composed of two wings *b'* *b''* at right angles, the one with the other, each wing consisting of a four-sided frame, the top and bottom pieces of which are flush with each other at the points of intersection. The said wings are made with sides inclined to an equal degree, the sides of *b'* inclining from the top inward, and those of the wings *b''* inclining from the bottom inward, so that the greatest lateral projections of the wings are at the tops of *b'* and bottoms of *b''*, and the least lateral projections at the tops of *b''* and bottoms of *b'*, while the least lateral projections of the wings, taken as wholes, are at the middle points of their height. The effect of this construction is to cause the greatest agitation of the cream to take place near the top and bottom of the churn, while the cream at the centre remains more calm, so far as the action of the dasher is concerned. The two dashers *b* are complementary to each other, being arranged so that those sides of the revolving wings which come nearest to each other are parallel. Now, it is evident that, since the stratum at the centre of the churn is calmest, the tendency of the currents is to flow in that direction, and that, consequently, the particles of butter as they form congregate at that part. The result of the employment of two dashers is to expel the particles from the ends of the churn, and cause them to collect between said dashers. All the butter in the churn then is massed at its middle part, and the aforesaid parallelism of the sides of the wings nearest each other gives the greatest amount of room for such massing that can be secured under this arrangement. The advantage of causing all the butter to collect at the centre of the churn is evident, since it not only greatly facilitates its removal, but also secures the greatest amount of butter from a given amount of cream, as the natural tendency of each particle toward the centre is far more efficacious in the way of preventing waste than the hands of any human manipulator.

Having thus fully described my invention, what I claim as new, and desire to secure by Letters Patent, is—

1. A churn-dasher, consisting of two wings set at any desired angle with each other, said wings being made with sides inclined in opposite directions, as and for the purpose set forth.

2. The dasher *b*, in combination with the band *c*, hook *d'*, and staple *e*, substantially as described.

JOHN T. COE.
